US00D999653S

(12) **United States Design Patent** (10) **Patent No.:** **US D999,653 S**
(45) **Date of Patent:** **** Sep. 26, 2023**

(54) **SURFACE ANALYSIS TOOL**

(71) Applicant: **Expertus Kemiteknik AB**, Sundsvall (SE)

(72) Inventor: **Lennart Sjölén**, Sundsvall (SE)

(73) Assignee: **EXPERTUS KEMITEKNIK AB**, Sundsvall (SE)

(**) Term: **15 Years**

(21) Appl. No.: **29/857,907**

(22) Filed: **Oct. 26, 2022**

Related U.S. Application Data

(62) Division of application No. 29/714,337, filed on Nov. 22, 2019, now Pat. No. Des. 980,729.

(57) **CLAIM**

The ornamental design for a surface analysis tool, as shown and described.

DESCRIPTION

FIG. 1 is a perspective view of a surface analysis tool according to first embodiment showing my new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is a perspective view of a surface analysis tool according to second embodiment;

FIG. 9 is a front view thereof;

FIG. 10 is a rear view thereof;

FIG. 11 is a top view thereof;

FIG. 12 is a bottom view thereof;

FIG. 13 is a left side view thereof; and,

FIG. 14 is a right side view thereof.
